US0D1066285S

(12) **United States Design Patent** (10) **Patent No.:** **US D1,066,285 S**
(45) **Date of Patent:** **** Mar. 11, 2025**

(54) **EARPHONE COVER**

(71) Applicant: **Amzaleg's LLC**, Woodland Hills, CA (US)

(72) Inventors: **Or Amzaleg**, Woodland Hills, CA (US); **Adam Amzaleg**, Woodland Hills, CA (US)

(73) Assignee: **Amzaleg's, LLC**, Woodland Hills, CA (US)

(**) Term: **15 Years**

(21) Appl. No.: **29/909,881**

(22) Filed: **Aug. 11, 2023**

(51) **LOC (15) Cl.** **14-01**

(52) **U.S. Cl.**

USPC **D14/205**

(58) **Field of Classification Search**

USPC D14/205, 249, 250; D29/112; 2/209; 381/380-381

(57) **CLAIM**

The ornamental design for an earphone cover as shown and described.

DESCRIPTION

FIG. 1 is a perspective view of a first embodiment showing the new design for an earphone cover;

FIG. 2 is a front view thereof;

FIG. 3 is a bottom view thereof, the bottom view is inset as shown in the front perspective view of FIG. 1;

FIG. 4 is a right side view thereof;

FIG. 5 is a left side view thereof;

FIG. 6 is a top view thereof; and,

FIG. 7 is a bottom view thereof.
